UNITED STATES PATENT OFFICE.

JAMES E. BRIGGS, OF WATERLOO, IOWA.

STREET-CLEANING MACHINE.

No. 926,723.

Specification of Letters Patent.

Patented July 6, 1909.

Application filed January 29, 1908. Serial No. 413,283.

To all whom it may concern:

Be it known that I, JAMES E. BRIGGS, a citizen of the United States of America, and a resident of Waterloo, Blackhawk county, 5 Iowa, have invented certain new and useful Improvements in Street-Cleaning Machines, of which the following is a specification.

My invention relates to improvements in street-cleaning machines, and the object of 10 my improvement is to provide a combined machine for sprinkling, then sweeping the litter on the street into a receptacle, said receptacle being furnished with suitable 15 enclosed mechanism for evacuating the contents at one side of the machine.

A further object is to so construct the sweeping mechanism, that it will operate to sweep the street clean to the curb line.

These objects I have accomplished by the 20 mechanism which is hereinafter described and claimed, and which is illustrated in the accompanying drawings, in which:

Figure 1 is an upper plan view of my said 25 improved street-cleaning machine. Fig. 2 is a side elevation thereof, and Fig. 3 is a detail view on a larger scale of the sprinkler-valve and the means for operating it. Fig. 4 is an enlarged perspective broken detail of the sectional receptacle.

Similar numerals refer to similar parts 30 throughout the several views.

The frame of my machine consists of a built-up and rigid structure, composed of 35 horizontal rectangular parts 67 and 69, spaced apart vertically by connecting uprights, with bracketed portions on both sides, the right-hand one adapted to support the extended operating parts of the mechanism on the same side. The pole 39 is secured to 40 the front transverse bars of the machine, while the forward part of such frame has 45 bearings for the ends of a rotatable transverse axle 1, to which the carrying-wheels 2 are secured to rotate therewith. The rear 50 part of the frame is carried on two casters 45, the pintles of each caster being rotatably mounted in bearings in the rear parts of brackets, the latter extending from vertical spindles 44 which are rotatable in bearings 55 supported by the rear transverse bars of the frame. The casters permit the machine to take a short turn when desired.

The sprinkling apparatus is supported at 55 the front of the machine, and the tank 29 is thus borne over the front carrying-wheels to

add to the tractive effort of their tread. Conduits 50 lead from the tank to valves in communication, on each side, with the risers 66 which in turn open into the transverse sprinkling pipe 36 which has a series of orifices on its under side. The valve-chambers 30 each contain a seat 50, contacted by a valve 64, the latter connected to a vertically-movable stem 59, such stem outside of the chamber having a pivotal connection 63 with the lower member of a bell-crank lever 57. The lever 57 has a fulcrum 62 on a supporting bracket 58, and the upper arm of said lever has a pivotal connection 60 to the outer end of one of the links 11, and the inner end 70 of each link 11 has a pivotal connection 61 to the lower end of a hand-lever 34. The hand-lever 34 has a fulcrum 65 on the tank 29, and may be shifted by the driver to open or close the valve-chambers 30 as desired. 75

The cylindrical broom 15 is secured to a transverse shaft 10, the ends of the latter being mounted in bearings in the rear ends of the arms 9 whose other ends are pivoted to a transverse rotatable shaft 21 supported by 80 the said frame. This broom is driven with a positive rearward rotation by means of the following mechanism: Sprocket-wheels 12 and 5 are secured to the shafts 10 and 21 respectively on their left-hand ends, and a 85 sprocket-chain 68 connects them. On the right-hand end of the shaft 21 is secured a sprocket-wheel 25 engaged by a sprocket-chain 26. The forward part of the chain 26 is passed about an idler 27 rotatably mounted 90 on a pin extending laterally from the forward end of an arm 42, the rear end of the latter being pivoted to a pin 53 extending from the upper part of an upright 7 on the frame 69. Another idler 8 is mounted on the same pin 95 53 as the rear end of the arm 42, and serves to direct the chain 26. The lower strand of said chain operatively engages the teeth of the driving-sprocket wheel 40 which is secured to the driving-axle 1. The chain 26 is 100 removed from operative engagement with said sprocket-wheel 40 by the shifting of a hand-lever 33 in one direction. This lever is medially pivoted on an upright 35 of said frame, and has a pawl adapted to ride over and engage the teeth of a rack-bar 47. An arm 31 is pivoted to the upright 7, and a connecting-rod 32 is pivotally connected between the arm 31 and said hand-lever, the 105 pivotal connection with the latter being by 110

means of a pin movable in an elongated slot 51 in said rod, whereby wear in the connecting parts of the machine is compensated for. A link 52 connects the arms 31 and 42, whereby, when the lever 33 is shifted in one direction, the arm 42 with the chain 26 is lifted, removing the latter from operative engagement with the driving-sprocket wheel.

The lower end of the lever 33 is extended 10 downward beyond its connection with rod 32, and to the end of the extension is attached the forward end of a chain or cable 24. The latter is then brought rearwardly to pass over an idler 23 to connect with the end of an arm 15 22 projecting from the transverse rock-shaft 14 in the rear end of the frame. This rock-shaft has forwardly bent arms whose ends are pivoted to the rear ends of links 13. A plurality of bearing perforations are alined in 20 the said links by which an adjustable connection is afforded with each end of the rock-shaft. The forward or lower ends of the said links are pivoted to the rear ends of the arms 9. When the lever 33 is shifted in one direction, by means of the said intermediate connections the broom may be elevated.

Closely anterior to and arranged in parallel with said broom is a rearwardly opening litter receptacle whose forward knuckle 71 is 30 pivoted on a transverse support 54 in said frame. The forward part of the receptacle is constructed of a single curved piece which, when elevated, lies near but not touching the transverse rotatable Archimedean screw 16. 35 This screw is mounted on a shaft 3 rotatable in said frame. By rivets 73 passed through registering orifices 72 a plurality of thin elastic and yieldable slats 55 are secured to said receptacle and to a plurality of parallel bars 46. The bars are arranged to overlap each other and said receptacle, so that when the slats 55 are bent into a curve the bars will have a slight relative movement to permit them to conform 40 to such curve. The receptacle, including all these parts is free to be bent and swung upwardly, the swinging taking place at the knuckle 71. To rings on the rear ends of the strips 55 are secured the rear ends of 45 50 chains or cables 17, the forward ends of which are connected to and adapted to be rolled upon the sleeve 18. The sleeve 18 is rotatably mounted upon the shaft 21, and bears a spool 19 to which is attached the rear end of another and single cable 20 to wind thereon, the forward end of the latter cable being connected to the lower end of a vertical shaft 48, turned by means of a crank 37, to wind thereon. When the chain 20 is wound 55 about the shaft 48, it is unwound from the spool 19, which in turning winds up the cables 17, and elevates the sections of the receptacle to a position where they almost contact with the screw 16, while the receptacle itself is thus raised a sufficient distance

above the street to dump with effect, in piles. The screw 16 in rotating, carries the litter in said receptacle out of the open side thereof, and can be started to rotate by the following described means. A sprocket-wheel 4 is secured to the left-hand end of the shaft 3, and a chain 6 passed about it and about an idler 27 pivoted to an arm 42 on the left side of the machine. A hand-lever 43 on the same side of the machine is connected 70 with the arm 42 by the same kind of connections as are shown on the other side as being connected between the lever 33 and the arm 42. When the lever 43 is shifted in one direction, the chain 6 is lowered into operative 80 engagement with the driving-sprocket wheel 40 on that end of the axle 1, which causes the screw 16 to be rotated until stopped by the lifting of the sprocket-chain.

It will be observed, on referring to Fig. 1, 85 that both the rotatable broom 15 and the receptacle 46 are extended at one side of the machine far enough to sweep and receive the litter on the street approximately to the outer line of the tread of the carrying-wheels, 90 which arrangement permits of the street being swept clear to the curb line. The extension may be on either or on both sides of the machine, as desired, the same principle of invention being involved.

Having described my invention, what I claim as new, and desire to secure by Letters Patent, is:—

1. In a street-cleaning machine, in combination, a frame mounted on transporting 100 means, a horizontal vertically-adjustable rearwardly-rotatable broom, and a rearwardly opening closed front trough mounted anterior to said broom and adapted to receive the sweepings therefrom and deliver them at one side of the machine, the said broom being adapted to sweep to approximately the outer line of the tread of said machine on the same side, said trough being adapted to be raised a distance above the 105 street, by swinging it upwardly, before discharging its contents to prevent clogging of its discharge opening.

2. In a street-cleaning machine, in combination, a frame mounted on transporting 115 means, a rotatable broom, said broom being adapted to sweep to approximately the outer line of the tread of the machine on one side, a rearwardly opening closed front trough mounted anterior to said broom and composed of relatively movable transverse 120 parallel sections, and means for swinging said movable sections to elevate said receptacle and close its open rear end.

3. In a street-cleaning machine, in combination, a frame mounted on transporting means, a rotatable broom, a rearwardly opening closed front trough mounted anterior to said broom, said receptacle being composed of a plurality of relatively-mov- 125 130

able transverse slats, and means within said receptacle for engaging the sweepings therein and carrying them out at one end thereof.

4. In a street-cleaning machine, in combination, a frame mounted on transporting means, a rotatable broom, a rearwardly opening closed front trough mounted anterior to said broom and supported by said frame, said receptacle being composed of relatively movable sections adapted to be swung vertically, and means within said receptacle for engaging the sweepings therein when desired and carrying them out at one end thereof.

5. In a street-cleaning machine, in combination, a frame mounted on transporting-wheels, a rotatable broom adapted to sweep to approximately the outer line of the tread of said transporting-wheels, a closed front trough supported by said frame and mounted anterior to said broom and adapted to receive the sweepings therefrom, said receptacle being composed of a plurality of relatively movable sections, means for swinging said sections vertically, and means within said receptacle for engaging the sweepings therein when desired and carrying them out at one end thereof.

6. In a street-cleaning machine, in combination, a frame mounted for transportation, a rotatable broom, a vertically movable contractile receptacle mounted anterior to said broom, both said broom and said receptacle being supported by said frame, means for swinging said receptacle upwardly and an Archimedean screw in said receptacle adapted to engage the sweepings therein as desired and carry them out of one end thereof, and means for independently positively rotating said screw.

7. In a street cleaning machine, in combination, a frame mounted on a rotatable axle at one end, having carrying-wheels secured thereto, a driving-sprocket wheel secured to said rotatable axle, a rotatable shaft mounted in said frame, a driven-sprocket wheel secured to said rotatable shaft, a vertically-movable broom supported by said frame, an arm pivoted to said frame having an idler-wheel rotatably mounted thereon, a hand-lever pivoted to said frame, connections between said hand-lever and said pivoted arm, a sprocket-chain about said driven-sprocket wheel and said idler wheel and adapted to be moved into or out of operative engagement with said driving-sprocket wheel by means of said hand-lever, pivoted arm and their connections, sprocket-wheels secured to said rotatable shaft and to the shaft of said broom, a sprocket-chain about said sprocket-wheels, and connecting means between said broom and said hand-lever, whereby said broom may be vertically adjusted away from the surface of the street by the action of the hand-lever.

8. In a street-cleaning machine, in combination, a frame mounted for transportation, a rotatable shaft in said frame, a driving-sprocket wheel secured to said rotatable shaft, another rotatable shaft mounted in said frame, a driven-sprocket wheel secured to said second shaft, a vertically movable broom supported by said frame, an arm pivoted to said frame having an idler-wheel rotatably mounted thereon, a hand-lever pivoted to said frame, connections between said hand-lever and said pivoted arm, a sprocket-chain about said driven-sprocket wheel and said idler-wheel and adapted to be moved into or out of operative engagement with said driving-sprocket wheel by means of said hand-lever, pivoted arm and their connections, sprocket-wheels secured to said second shaft and to the broom-shaft, a sprocket - chain movable about said sprocket-wheels, and connecting means between said hand-lever and said broom adapted to elevate said broom away from the street surface when said hand-lever is shifted in one direction.

9. In a street-cleaning machine, in combination, a frame mounted for transportation, a rotatable broom supported by said frame, a vertically-swinging receptacle supported anterior to said broom and adapted to receive the sweepings therefrom, a rotatable shaft in said frame parallel to said receptacle, a pulley fixed on said shaft, a rotatable spindle in said frame, a cable connected between said pulley and said spindle, and cables connected between said rotatable shaft and the rear part of said receptacle adapted to tilt the open receiving-end thereof upwardly to prevent escape of its contents at that end.

10. In a street cleaning machine, in combination, a frame mounted for transportation, a rotatable broom operatively mounted therein, a receptacle supported by said frame in advance of said sweeping means, closed to the front and open toward the rear when lowered, said receptacle being composed of a contractile sectional trough, means for swinging said trough upwardly and means in said receptacle adapted to deliver its contents at one side of the machine when the latter is elevated.

11. In a street cleaning machine, in combination, a frame mounted for transportation, a rotatable broom operatively mounted therein, a receptacle hinged to said frame and depending therefrom in front of such sweeping-means and open at the rear to receive sweepings from said means and closed at the front to prevent escape of said contents, said receptacle being composed of transverse parallel sections, elastic strips connected to all the sections, and operative means connected to the rear edge of said receptacle and adapted to raise and lower it,

by means of swinging upward the movable sections.

12. In a street cleaning machine, in combination, a frame mounted for transportation, a rotatable broom operatively mounted therein, a receptacle hinged to said frame in front of said sweeping-means, open at the rear but closed at the front, said receptacle being composed of relatively-movable trans-
10 verse parallel sections, resilient plates connecting said sections, means connected to the rearmost part of said receptacle and adapted to simultaneously raise said sections by swinging them upward, and a rota-
15 table Archimedean screw located and mount-

ed transversely above said receptacle and adapted, when said receptacle has been swung upward about its lower side, to carry the contents of the receptacle and deliver them from one end thereof at one side of the 20 machine at a desired height above the street level.

Signed at Waterloo, Iowa, this 11th day of Jan. 1908.

JAMES E. BRIGGS.
